UNITED STATES PATENT OFFICE.

FREDERICK WILLIAM VOGT, OF PHILADELPHIA, PENNSYLVANIA; EMMA M. VOGT
ADMINISTRATRIX OF SAID FREDERICK WILLIAM VOGT, DECEASED.

DEVICE FOR RESISTING SWINGING MOVEMENTS OF SUSPENDED RAILWAY-CARS.

No. 919,268.

Specification of Letters Patent.

Patented April 20, 1909.

Application filed February 24, 1908. Serial No. 417,556.

To all whom it may concern:

Be it known that I, FREDERICK WILLIAM VOGT, residing at Philadelphia, in the county of Philadelphia and State of Pennsylvania, have invented certain new and useful Improvements in Devices for Resisting Swinging Movements of Suspended Railway-Cars, of which the following is a specification.

My invention has relation to a device for counteracting swinging movements of railway cars of the type and construction illustrated and described in the issue of the "Engineer", London, of October 24th, 1902, which by gravity are held in an operative position suspended from a structure, and in such connection it relates more particularly to mechanism connected with the car, which by developing and bringing forces similar to those developed in a gyroscope into action, 20 resists and thus counteracts the swinging movements of the suspended car, which are caused by wind pressure or high speed of travel.

The nature and scope of my invention will 25 be more fully understood from the following description taken in connection with the accompanying drawing, illustrating partly in elevation and partly in section a portion of a supporting structure, a car suspended therefrom, and the mechanism, forming the subject matter of the present application, connected with the car.

Referring to the drawings, 1 represents the car to the roof 2 of which is suitably secured a bracket 3, supporting a traction-wheel 4, and a casing 7 inclosing a motor, not shown, for driving the wheel by means of a gear-wheel 13. The wheel 4 engages a rail 5 carried by a structure 6, which forms the 30 support from which the car 1, by means of the bracket 3, is suspended. Preferably on the roof 2 of the car 1 are arranged brackets 8, supporting a shaft 9, to which are secured disks or fly-wheels 10, a gear-wheel 11 and a 35 brake-disk 12. The gear-wheel 11 meshes with a gear-wheel 15 of an electric motor 14, likewise placed on the roof 2 of the car, which motor by means of its gear-wheel 15 and the gear-wheel 11, sets the shaft 9 and the disks 40 10 mounted thereon in rapid rotation, in a direction similar to that in which the traction-wheel 4 is rotated. As long as the car 1, by force of gravity, is held in a vertical position, the forces which have been developed 45 by the rapid rotation of the shaft 9 and disks 50 10 mounted thereon in rapid rotation, in a direction similar to that in which the traction-wheel 4 is rotated. As long as the car 1, by force of gravity, is held in a vertical position, the forces which have been developed 55 by the rapid rotation of the shaft 9 and disks

10, remain inactive. As soon however as the car is moved out of its normal vertical position and is inclined as well as the shaft 9, these forces are brought into action and oppose in a well known manner such movements of the shaft 9. Thus the shaft 9 will counteract, by the intervention of the brackets 8, the swinging movement of the car 1, and will thus aid the force of gravity to move the car back to its normal vertical position, 60 and to maintain the same therein.

In order to stop the action of the forces developed by the rotation of the shaft 9 and disks 10, a brake-band 16 engaging the brake-disk 12 and when tightened thereon, by 65 means not shown, will prevent the further rotation of the shaft 9 and disk 10, and will then permit the car to swing sidewise, under the action of centrifugal force, in taking curves in the rail 5, on the supporting structure 70 6.

Having thus described the nature and object of my invention, what I claim as new and desire to secure by Letters Patent is:—

1. In a device of the character described, a 80 structure, a car suspended from said structure and held in a normal operative position by gravity, a shaft having disks, and means for rotating said shaft and disks, said shaft and disks when rotated adapted to resist 85 swinging movements of said car.

2. In a device of the character described, a 90 structure, a car suspended from said structure and held in a normal operative position by gravity, a shaft, means for connecting said shaft with said car, disks mounted on said shaft, means for rotating said shaft and disks, said shaft and disks when rotated adapted to counteract swinging movements of said car. 95

3. In a device of the character described, a 100 structure, a rail carried by said structure, a car having a traction-wheel traveling on said rail, said wheel adapted to hold said car suspended from said rail and permit of holding of the car by gravity in a vertical operative position thereon, a shaft having disks, means for rotating said shaft and disks, and said shaft and disks when rotated adapted to resist swinging movements of said car. 105

4. In a device of the character described, a 110 structure, a rail carried by said structure, a wheel traveling on said rail, a car, means for connecting said wheel with said car, said wheel in conjunction with said means adapt-

ed to hold said car suspended from said rail, a shaft carried by said car and held by the same in a position at right angle to said wheel, disks mounted on said shaft, and 5 means for rotating said shaft and disks, said shaft and disks when rotated adapted to assist force of gravity to return said car to a vertical position when removed therefrom.

5. In a device of the character described, a 10 structure, a rail carried by said structure, a wheel traveling on said rail, a car having a roof, means for connecting said wheel with said car, said wheel in conjunction with said means and said roof adapted to hold said car 15 suspended from said rail, brackets carried by said roof, a shaft carried by said brackets and held by the same in a position at right angle to said wheel, disks carried by said shaft, means for rotating said shaft and by 20 the same said disks, said shaft and disks when rotated adapted to assist the force of gravity to return said car to a vertical position when removed therefrom.

6. In a device of the character described, a 25 structure, a rail carried by said structure, a wheel traveling on said rail, a car, means for connecting said wheel with said car, said wheel in conjunction with said means adapted to hold said car suspended from said rail, 30 a shaft carried by said car and held by the same in a position at right angle to said wheel, disks mounted on said shaft, means for rotating said shaft and disks, said shaft and disks when rotated adapted to resist swinging movements of said car, and means for 35 arresting the rotary movement of said shaft and disks.

7. In a device of the character described, a 40 structure, a rail carried by said structure, a car having a traction-wheel traveling on said

rail and adapted to hold said car suspended therefrom, brackets carried by said car, a shaft carried by said brackets and held by the same in a position substantially at right angle to said wheel, disks and a gear-wheel 45 mounted on said shaft, means meshing with said gear-wheel adapted when actuated to rotate said shaft and by the same said disks, said shaft and disks when rotated adapted to aid the force of gravity in returning the car 50 to a normal operative position when removed therefrom, and means carried by said shaft adapted to arrest the rotary movement thereof.

8. In a device of the character described, a 55 structure, a rail carried by said structure, a car having a traction-wheel traveling on said rail, said wheel adapted to hold said car in a suspended position from said rail, brackets carried by said car, a shaft carried by said 60 brackets and held by the same in a position substantially at right angle to said traction-wheel, disks, a gear-wheel and a brake-disk mounted on said shaft, a motor carried by said car having a gear-wheel meshing with 65 the gear-wheel of said shaft and adapted by the intervention of the gear-wheels to set said shaft and disks in rapid rotation, said shaft and disks when rotated adapted to aid the force of gravity in returning the car to a 70 normal operative vertical position when removed therefrom, and means engaging the brake-disk of said shaft.

In witness whereof, I have hereunto set my signature in the presence of two subscribing witnesses.

F. WILLIAM VOGT.
